US00D357465S

United States Patent [19]

Iino

[11] Patent Number: Des. 357,465

[45] Date of Patent: ** Apr. 18, 1995

[54] ELECTRONIC COMPUTER

[75] Inventor: **Masaaki Iino**, Yokohama, Japan
 [73] Assignee: **Kabushiki Kaisha Toshiba**,
 Kanagawa, Japan

[**] Term: **14 Years**[21] Appl. No.: **12,026**[22] Filed: **Aug. 20, 1993**

[30] Foreign Application Priority Data

CLAIM

The ornamental design for an electronic computer, as shown and described.

DESCRIPTION

FIG. 1 is a top, front and right side perspective view of an electronic computer showing my new design;
 FIG. 2 is a front elevational view thereof;
 FIG. 3 is a left side elevational view thereof;
 FIG. 4 is a right side elevational view thereof;
 FIG. 5 is a rear elevational view thereof;
 FIG. 6 is a top plan view thereof;
 FIG. 7 is a bottom plan view thereof;
 FIG. 8 is a front elevational view thereof in closed position;
 FIG. 9 is a top plan view thereof in closed position;
 FIG. 10 is a left side elevational view thereof showing in closed position;
 FIG. 11 is a top, front and right side perspective view thereof showing keyboard separated from computer; and,
 FIG. 12 is a top, front and left side perspective view thereof in closed position and carrying handle in set up position.
